UNITED STATES PATENT OFFICE.

WILLIAM F. MOSSOP, OF PHILADELPHIA, PENNSYLVANIA, ASSIGNOR OF
ONE-HALF TO MORRIS M. HIRSCH, OF CHICAGO, ILLINOIS.

CONVERTIBLE FREIGHT-CAR.

SPECIFICATION forming part of Letters Patent No. 357,937, dated February 15, 1887.

Application filed October 13, 1886. Serial No. 216,089. (No model.)

To all whom it may concern:

Be it known that I, WILLIAM F. MOSSOP, a citizen of the United States, residing at Philadelphia, in the county of Philadelphia and State of Pennsylvania, have invented certain new and useful Improvements in Convertible Grain and Freight Cars; and I do hereby declare the following to be a full, clear, and exact description of the invention, reference being had to the accompanying drawings, which form part of this specification, in which—

Figure 1 is a vertical longitudinal section of a car embodying my improvements. Fig. 2 is a horizontal section on line $x x$ of Fig. 1, the 15 adjustable floor-sections being omitted. Fig. 3 is a vertical transverse section on line $y y$ of Fig. 1. Fig. 4 is a side elevation of a detail, shown on more enlarged scale than the other figures. Fig. 5 is an end elevation, partly broken away, of cover of discharge-spout. Fig. 6 is a vertical section of discharge-spout and cover. Fig. 7 is a side elevation of car-door and guides. Fig. 8 is an elevation of car-door. Fig. 9 is a perspective of hinge for door-slats.

25 My invention has for its object to provide an improved construction of a convertible car having a floor which may lie horizontally for the reception of ordinary freight or general merchandise and be adjusted for a grain-car having inclined planes leading to a centrally-located discharge-hopper.

30 My improvements consist in the peculiar construction and combinations of parts hereinafter described and specifically explained.

35 Referring to the accompanying drawings, A designates the body of the car mounted on trucks B B.

40 C C are the side sills, and D, D', and E the intermediate sills, on which the bottom or floor of the car is supported. The middle sill, E, does not extend the full length of the car, being separated near the center, forming an opening which receives a hopper, F.

45 G G are short transverse sills extending from the sill D to the sill D', and secured thereto by angle-irons or knee-plates g g.

The hopper F has two horizontal lateral flange-plates, f f, which extend over to the sills C C and rest upon and are bolted to the latter,

as well as upon and to the sills D D'. On each 50 of these flange-plates are formed racks f' f', the purpose of which will be hereinafter explained.

H is a transverse beam or girder extending laterally across and above the hopper, resting on the flange-plates f f, and secured to the same. 55 This girder has its two upper sides beveled or inclined, as shown. The neck f' of the hopper has a swiveled spout or discharge-pipe, F', which can be readily turned around to discharge upon either side of the car. 60

I and I' are permanent or stationary parts of the floor, one at each end of the car, and K and K' are adjustable sections of said floor, and, when lying horizontally, extending from said stationary parts to the girder or cross-beam H. 65 These floor-sections are each composed of cross-boards or flooring-pieces fastened to longitudinal girders or beams of T-iron. The inner ends of said adjustable sections K K' are provided with anti-friction rollers k k, (shown in 70 the detail, Fig. 4,) which rest and run upon the flange-plates f f, and they have also paws k' k', as shown in said figure, which engage with the racks f' f', Fig. 2. The opposite ends of said sections are provided with laterally-projecting 75 pins or trunnions k' k', which enter inclined slots l l in guides L L on the sides of the car. These trunnions extend into the spaces m m between the double walls M, and in said spaces are chains n n, which are wound upon shafts N 80 N by means of worm-shafts O O, having handles o o outside of the ends of the cars.

P and P are inclined bars or cleats on the inner side walls of the car, and p p are sections of rubber tubing just below said cleats, which 85 form tight joints with the floor-sections K K' when the latter are elevated, and prevent leakage of grain.

When the car is to be used as an ordinary freight-car or for general merchandise, the floor-sections K K' are disposed horizontally, as shown in the left of Fig. 1, forming, with the stationary parts I I', a continuous floor and covering the hopper, meeting end to end over the transverse girder H. When it is desired to 90 use the car for grain, the sections K K' are raised by means of the end gearing until they 95 assume the inclined position, as shown in the

right in Fig. 1, the pawls k' engaging with the racks f' and assisting the chains $n\ n$ in holding said sections $K\ K'$ in their inclined positions.

As means for closing the discharge-spout or its swiveled end, I provide the latter with a cover or end, T . (Shown in Figs. 5 and 6.) This end is in the form of a sliding plate having top and bottom flanges, $t\ t$, in which are formed grooves, which receive tongues f^3 on the spout when said plate is applied to the spout, as it may be by a lateral edgewise movement. Said plate has a handle, t' , to facilitate its movement.

To lock the end plate, T , it is provided with a spring-latch, U , in a recess, T' , in an offset, which latch is adapted and designed to enter a notch or recess, f^4 , on one of the tongues, and a key may be provided for lifting the latch when it is desired to open the spout by removing the end T . To prevent the grain from rushing out of the spout in the act of removing the end plate, said spout has an internally-located flap or gate, V , hinged at v , which is normally held stationary by a pin, v' , secured to a spring-arm, v^2 , fastened to the spout, as shown. On pulling down the pin after removing the end plate the flap or gate V will be raised and kept elevated by the pressure of the grain discharging through the spout.

The car-door is preferably a hinged slat door, W , as shown in Fig. 7, which moves in guides, as shown in Fig. 8, the form of hinge used being shown in Fig. 9.

What I claim as my invention is—

1. In a convertible grain and general freight car having a central hopper, a floor consisting of fixed or stationary end sections, $I\ I'$, and adjustable sections $K\ K'$, substantially as shown and described.

2. In a convertible grain and general freight 40 car, a hopper having laterally-extending flange-plates ff with racks $f'f'$, in combination with adjustable floor-sections $K\ K'$, having pawls $k\ k$, substantially as shown and described.

3. In a convertible grain and general freight 45 car, the combination, with adjustable sliding floor-sections $K\ K'$, of windlasses for moving the same, inclined guides L , with slots l , and trunnions $k\ k$, said trunnions extending into spaces in the car-walls and the windlass-chains being concealed or contained in said spaces, substantially as shown and described.

4. In a car having adjustable inclined floor-sections $K\ K'$, the combination, with said sections, of inclined cleats L and cushions l , forming tight joints to prevent leakage of grain, substantially as shown and described.

5. In combination with the discharge-spout F' , having tongues f^3 , the sliding end plate, T , having flanges $t\ t$, which engage with said tongues, and a latch for locking said plate on said spout, substantially as shown and described.

6. The combination, with the spout F , of 65 flap or hinged gate V and pin v' , said gate being wholly inside the spout and said pin having one end extending through the wall of the spout, substantially as shown and described.

In testimony that I claim the foregoing I have 70 hereunto set my hand this 9th day of October, 1886.

WILLIAM F. MOSSOP.
